FLASHER

Carl H. Larson, Elkhart, Ind., assignor to The
Adlake Company, a corporation of Illinois

Application November 15, 1932, Serial No. 642,740

10 Claims. (Cl. 200—97)

There are two types of highway crossing signals in general use which conform to the recommended practice. The first of these is the flashing light type in which two lamps, spaced approximately two and one-half feet apart, are mounted on a horizontal support and alternately flashed; and the other, known as the wig-wag type in which a pendulum disk is oscillated and carries on its end a red light. It is the first of these two types of crossing signals to which this invention is directed.

Electrical apparatus commonly used for producing the intermittent flashes of the lamps is illustrated and described in American Railway Signaling Principles and Practices, Chapter 6, Direct current relays, published by the Signal Section, A. R. A., 30 Vesey St., New York, N. Y. It will be observed that these relays are all of the mechanical type and are consequently open to the usual objections, the principal one of which is that the contacts become pitted or worn and require frequent attention.

In the flasher relay of this invention, all mechanical contacts have been eliminated and mercury switches are used in their place. The fact that all electrical contacts of the mercury switch relay are hermetically sealed within a glass envelope and in consequence are not subject to the deteriorating effects of the atmosphere, is but one of the advantages of this type of relay.

Other advantages which may be briefly mentioned reside in the elimination of bearings and movable parts, the constant and extremely low contact resistance unaffected by temperature changes of 40° below zero to 300° above zero, the lack of wear on the contact material, the noiseless operation on both alternating current and direct current, economy of space due to compact mounting, and the complete elimination of the necessity for inspection and maintenance.

As the disclosure proceeds, it will also be seen that the flasher relay of this invention is much less expensive to operate as the control circuit is open about fifty percent of the time that the relay is in operation.

Further and other objects and advantages will become apparent as the following description is read in conjunction with the drawings, in which—

Fig. 1 is a circuit diagram showing a preferred form of the invention, adapted to be operated from a double track circuit;

55 Figs. 2, 3 and 4 illustrate other positions of the

self-acting intermittent circuit breaker in a control circuit;

Figs. 5 and 6 illustrate other positions of the electro-magnetic switch in the main circuit;

Fig. 7 shows a modification in which front 5 and back contact mercury switches are substituted for the three electrode switch shown in the preferred form of the invention;

Fig. 8 is a view similar to Fig. 7 showing the switch parts in the position they assume when 10 the associated coil is energized;

Fig. 9 is a rear view of the relay mounting; and

Fig. 10 is a diagrammatic perspective view 15 of the relay, its housing, and a crossing signal connected to the relay.

The specific disclosure of preferred and modified forms of the invention is not to be interpreted as imposing limitations upon the appended claims except as may be required by 20 the prior art.

Referring first to Fig. 1, a preferred form of the invention is illustrated as applied to a double track road with traffic in the direction of the arrows. The electrical apparatus consists 25 of a track circuit, a control circuit and a main circuit, the latter two of which are held open by the track circuit until a train comes within a certain distance of the crossing which is to be protected. The control circuit includes a self- 30 acting intermittent circuit breaker generally designated 10 which opens and closes the control circuit at regular intervals. The main circuit includes the lamps 11 and 12 which are alternately flashed by an electromagnetic switch 13 35 which is governed by the control circuit. It will be understood that the lamps 11 and 12 are mounted on a horizontal support 14 (Fig. 10) adjacent to the crossing which is being protected. The flasher relay generally designated 15, 40 which combines the control and main circuits constitutes a unit that may be mounted in a suitable box alongside the track.

Track circuit

45

In Fig. 1, there is illustrated a suitable track circuit for a double track road with traffic on each track in one direction only. The track 16, with traffic to the left (Fig. 1) is provided with insulated rail joints 17 and 18 which enable a 50 potential to be applied between the opposed rails of the track to normally maintain the coil 19 of the track relay, generally designated 20, in energized condition. The potential is applied through a transformer 21 which reduces the 110 55

volt source of alternating current to 10 volts. At a point adjacent the insulated rail joint 17, a transformer 22 is connected across the opposed rails to complete the circuit, the secondary coil 23 of the transformer being connected to a rectifier 24 which in turn is connected to the coil 19. When the train enters the section of track between the insulated joints 18 and 17, the circuit between the transformers 21 and 22 will be short circuited, and in consequence the relay coil 19 becomes de-energized, allowing the armatures 25 and 26 to fall on their respective contacts 27 and 28.

In a like manner, the track 29 whose traffic is to the right, Fig. 1, is provided with insulated rail joints 30 and 31. A potential is applied across the opposed rails of the track as before, the electrical energy being derived from a 110 volt line connected to a transformer 32 which reduces the voltage to 10 volts. A transformer 33 connected across the opposed rails adjacent the insulated rail joint 31 completes the circuit and through its secondary coil 34 supplies energy to the rectifier 35, which in turn energizes the relay coil 36. When the train enters the section of track between the insulated rail joints 30 and 31, the circuit between the transformers 32 and 33 is shorted and in consequence, the armatures 37 and 38 are permitted to fall upon their respective contacts 39 and 40.

The armatures 25 and 37 are electrically connected to each other and to the conductor 41 which is in the control circuit. The contacts 27 and 39 are also connected to each other and to the conductor 42 in the control circuit. The control circuit is, therefore, held open by the relay coils 19 and 36 whenever the tracks 16 and 29 are clear between the insulated rail joints 18 and 17, and 30 and 31, respectively, but as soon as a train enters either of these sections, one of the coils of the track relays 20 completes the control circuit.

In a like manner, the main circuit is held open until a train short circuits the track circuit at which time either the armature 26 falls upon the contact 28, or the armature 38 falls upon the contact 40. Since the armatures 26 and 38 are electrically connected to each other and to a conductor 43 in the main circuit, and since the contacts 28 and 40 are also connected to each other and to a conductor 44 in the main circuit, the falling of either armature upon its associated contact will close the main circuit.

It is, of course, understood that when a train on track 16 passes the insulated rail joint 17, or a train on track 29 passes the insulated rail joint 31, the track circuit is again established and the control and main circuits are broken.

Control circuit

The purpose of the control circuit is to intermittently energize the electromagnetic switch 13. This is accomplished by providing a self-acting intermittent circuit breaker 10 in the control circuit. The control circuit is energized by a battery 45 although any other suitable source of current may be employed, if desired.

Two solenoids 46 and 47 connected in series are associated with the circuit breaker 10, and two other solenoids 48 and 49 also connected in series are associated with the electro-magnetic switch 13. The two groups of solenoids, however, are connected in parallel as will later be seen.

The circuit breaker 10 comprises a glass en-

velope 50 vertically mounted between pole pieces 51 and 52, the former being associated with the solenoid 47 and the latter with the solenoid 46. As the two solenoids are connected by a bar of magnetic material 53, a magnetic circuit is formed which is closed except for the air gap between the pole pieces 51 and 52.

A quantity of mercury 54 is placed in the envelope to bridge the electrodes 55 and 56 when the displacer 57, which is made of magnetic material, is in the position shown in Fig. 1. The electrode 56 is connected by a conductor 58 to the conductor 59 which joins solenoid 46 with solenoid 48, and the electrode 55 connects with the conductor 41 so that when the electrodes are bridged by the mercury, the closing of the control circuit by the track relay 20 will immediately energize the solenoids 46 and 47. The circuit is then traceable from the battery through the conductor 60, solenoids 47 and 46, conductor 59, conductor 58, electrode 56, mercury 54, electrode 55, conductor 41, armature 37 or 25, contact 39 or 27, conductor 42, and back to the battery.

However, as soon as the solenoids 46 and 47 are energized, the plunger 57 is lifted in its effort to close the air gap in the magnetic circuit. When this occurs, the mercury displaced by the lower portion 61 of the plunger recedes in the envelope and uncovers the electrode 55 (see Fig. 3) causing the control circuit to be broken. Thereupon the plunger 57 by its own weight falls once more to the position shown in Fig. 1 and reestablishes this circuit, the intermittent making and breaking of the circuit taking place as long as the control circuit is closed by the de-energization of relay coil 19 or 36.

Since the recommended practice of the American Railway Association requires that there be a certain time interval between the light flashes, it is necessary to provide some means for controlling the intervals at which the control circuit is broken and reestablished. This is accomplished in the present invention by closing the top of the plunger 57 and providing an aperture 62 into which a plug 63 is adapted to be adjustably seated. A gas trap 64 is, therefore, formed with the only means of escape for the gas being past the plug 63 in the aperture 62. The plug may be tapered on one side so that as the plug is forced deeper into the plunger, the aperture is proportionately reduced in size.

By this arrangement, when the solenoids 46 and 47 are energized, the plunger 57 is raised and picks up a quantity of mercury as shown in Fig. 2. The slow admittance of gas into the trap 64 through the aperture 62 delays the levelling of the mercury on the inside and outside of the plunger for a given period of time. When sufficient gas has been admitted into the interior of the plunger to balance the pressure between the inside and outside of the plunger, the mercury occupies a position such as shown in Fig. 3 and the control circuit is broken. Thereupon, the plunger falls, as shown in Fig. 4, but once again the gas trap functions to delay the mercury in adjusting its level and in consequence, the mercury within the plunger is held away from the central electrode 55 until sufficient gas has escaped from the trap 64 to equalize the pressures on the inside and outside of the plunger. The switch then assumes the position shown in Fig. 1 and the operation is repeated.

The plunger 57 is preferably formed as a

sleeve in which the upper portion 65 is substantially thicker than the lower portion 61. The purpose of this is to make the potential energy of the plunger when in its raised position 5 substantially equal to the magnetic energy necessary to raise the plunger from its depressed position, for in this way the time interval for closing the circuit is substantially equal to the time interval for opening the circuit. Obviously, the plunger may assume a different form 10 in accomplishing the same purpose, but preferably is in the form shown in Fig. 1 because in this form, the mass of the upper portion 65 of the plunger is close to the glass envelope 15 where the magnetic efficiency of the solenoids 46 and 47 is maintained at a maximum.

By way of example, the plunger may have an overall length of three inches, an outside diameter of five-sixteenths of an inch at the upper 20 portion 65, an inside diameter of $\frac{3}{16}$ of an inch for the same portion. The outside diameter of the lower portion may be $\frac{1}{4}$ of an inch and the inside diameter $\frac{3}{16}$ of an inch. With these dimensions, the lower portion 61 should constitute approximately one-half of the total length 25 of the plunger.

Also, by way of example, the solenoids 46 and 47 may be wound with 28 gauge, enameled copper wire having approximately 9000 turns per 30 coil, ohmic resistance of 188 ohms per coil, with an actual current consumption of $26\frac{1}{2}$ milliamperes, and a steady current consumption of 35 53 milliamperes.

The glass envelope 50 is preferably filled with 35 an inert gas such as helium, hydrogen, or the like, and springs 66 are provided at the top and bottom of the plunger to prevent possible breakage of the envelope while the relay is being shipped.

In operation, the plunger drops to its lowermost position (with the bottom spring resting 40 on the floor of the switch envelope) as soon as the coil is de-energized, without coming to a position of floating equilibrium during the downward travel. This is effected by the distribution 45 of mass in the plunger and its relation to the amount of mercury in the envelope. Thus the action of the plunger is characterized by relatively quick, positive action in both directions in response to the coil, and the time delay 50 in making or breaking the circuit through the electrodes is consequently directly dependent upon the operation of the gas trap in the plunger without being functionally related to the speed of plunger travel.

The switch envelope is held within the poles 55 51 and 52 in any suitable manner. A convenient way for holding the switches in place is by slipping them through a bakelite sleeve 67 which 60 has internal and outside diameters corresponding to the switch envelope and which is split longitudinally as shown at 68 to permit the sleeve to accommodate the envelope.

Main circuit

From what has been said about the control circuit, it is obvious that the solenoids 48 and 49 are intermittently energized in synchronism with the making and breaking of the control circuit. Throughout this specification and the 70 claims, it will be understood that "synchronism" is intended to mean "at similar time intervals" and is not necessarily to be construed as meaning simultaneous action.

The main circuit is energized by the secondary

coil 69 of a transformer 70, the primary coil 71 of which is connected to the usual 110 volt source of alternating current.

The electromagnetic switch 13 comprises a switch envelope 72 through the bottom of which electrodes 73, 74 and 75 are sealed. A quantity of mercury 76 is placed in the envelope and is adapted to bridge electrodes 73 and 75, or electrodes 74 and 75, according to the position of the displacer 78 within the envelope. Springs 77 are placed above and below the displacer to protect the envelope from possible injury.

In accordance with railroad parlance, the electrode 73 will be termed a back contact because it establishes a connection when the associated 15 solenoids are deenergized, and the electrode 74 will be termed a front contact because it establishes an electrical connection when the associated solenoids are energized.

The electrode 75 is connected by a conductor 20 79 with one side of the secondary coil 69, the other side of the coil being connected by conductors 44 and 43 through the track relay 20 and thence to the conductor 80 joining the lamps 11 and 12. The electrodes 73 and 74 are connected to the other terminals of the lamps 25 11 and 12 by conductors 81 and 82, respectively.

The plunger 78 is constructed so that when it is in its lower position (Fig. 1), the electrode 74 is out of contact with the mercury and the electrodes 73 and 75 are bridged by the mercury. Assuming that the track relay has closed the main circuit, the latter circuit may be traced from the secondary coil 69, thru the conductor 79, electrode 75, mercury 76, electrode 73, conductor 81, lamp 11, conductor 80, conductor 43, track relay 20, conductor 44, and back to the secondary coil.

When the plunger is in the position shown 40 in Fig. 6, the electrode 73 is out of contact with the mercury and the electrodes 74 and 75 are electrically connected by the mercury. The circuit may then be traced from the secondary coil 69 through conductor 79, electrode 75, mercury 76, electrode 74, conductor 82, lamp 12, conductor 80, conductor 43, track relay 20, conductor 44, back to the secondary coil. Therefore as the plunger 78 is reciprocated within 45 the envelope, the lights 11 and 12 are alternately flashed.

The switch 13 may be of the type shown in my copending application, Ser. No. 636,288, filed October 5, 1932, the specific form being shown in Figs. 7 to 12 of that application. It will be understood that the switch is so formed that whenever the plunger changes its position, there will always be an intermediate position, such as shown in Fig. 5, at which time, the electrodes 73 and 74 are both out of contact with the mercury.

The solenoids 48 and 49 may have the same characteristics as previously given for the solenoids 46 and 47.

In place of the three-electrode switch shown 65 in Figs. 1, 5 and 6, it is possible to substitute front and back contact mercury switches, such as shown in Figs. 7 and 8. In this arrangement, the front contact switch indicated at 83 is provided with electrodes 84 and 85 which are disconnected from each other whenever the solenoids 48 and 49 are de-energized (Fig. 7.) Under such circumstances, the plunger 86 floats 70 high upon the mercury 87.

When the solenoids 48 and 49 are energized, the plunger 86 is drawn down into the mercury 75

and the electrode 84 is then covered with mercury, as seen in Fig. 8. The pole sleeves 88 and 89, which are made of magnetic material, serve to fix the air gap at the desired place with 5 reference to the electrode 84.

The back contact switch 90 has electrodes 91 and 92 which are adapted to be bridged by the mercury 93 within the envelope whenever the solenoids 48 and 49 are de-energized. When 10 the plunger is drawn up by the energization of the solenoids (Fig. 8) the mercury recedes from the electrode 91 and the connection between the electrodes 91 and 92 is broken. The pole sleeve 94 serves to fix the position of the 15 air gap.

The pole pieces 95 and 96 used with separate front and back contact switches differ from the pole pieces 97 and 98, shown in Fig. 1 and Fig. 9, only by being provided with suitable apertures 20 for the extra switch.

As shown in Fig. 7, the electrode 84 of the switch 83 and the electrode 92 of the switch 90 are connected by a conductor 99 which in turn is connected to one side of the secondary 25 coil 69 of the transformer 70. The lamps 11 and 12 have one terminal each connected to the electrodes 85 and 91, respectively, while the other terminal of each lamp is connected by a conductor 80. The conductor 43 leading to the track relay 20, which in turn is connected by conductor 44 to the other side of the secondary coil 69, completes the circuit.

Structure

35 The physical structure of the relay is best shown in Figs. 9 and 10.

The relay includes a housing 100 adapted to be secured to a vertical wall. The front of the housing is adapted to be closed by an insulating plate 101, upon which the relay mechanism is mounted. On the front of the plate 101 are mounted the solenoids 46, 47, 48 and 49, the tops of the first two being connected by a magnetic bar 53 and the tops of the second two 45 being connected by a magnetic bar 102.

The cores 103 of the respective solenoids have both ends threaded, the inner ends passing through the insulating plate 101 and screwing into the pole pieces 51, 52, 97 and 98, and the other 50 ends passing through the bars 53 and 102 and fitted with nuts. A bar 104 of nonmagnetic material (Fig. 9) is placed between the pole pieces 51, 97 and 52, 98, respectively, in order to prevent the pole pieces from being rotated 55 and possibly breaking the switch tubes.

The circuit breaker 10 and switch 13 are mounted in their respective pole pieces and held in place by the bakelite sleeves 67. The electrode 56 of the circuit breaker 10 is connected 60 to a binding post 105 and the other electrode 55 is connected to a binding post 106 which connects the two groups of solenoids. The electrode 75 of the switch 13 is connected to a binding post 107, the electrode 74 to a binding post 65 108, and the electrode 73 to a binding post 109. Other binding posts are provided as follows: Binding post 110 is connected by conductor 111 70 to binding post 112; binding post 113 is connected by a conductor 114 to binding post 112; binding post 115 is connected by a conductor 116 to binding post 117, the latter binding post joining the two groups of solenoids in parallel; binding posts 118 and 119, which connect the solenoids of each group in series.

75 As seen in Fig. 10, binding posts 105 and 115

are connected to the battery 45; the binding posts 107 and 110 are connected to the secondary coil 69, and the track relay, respectively; the binding posts 108 and 112 are connected to the lamp 12 and the binding posts 113 and 119 are connected to the other lamp 11. 5

The flashing light signal which has just been described has fewer parts than the mechanical flashers heretofore employed, and in addition has far greater reliability in operation. It is, 10 of course, understood that the device is not limited to use at railroad crossings, but may be used wherever a flashing signal is desired. If the device is used to protect dangerous points on a highway and under those circumstances 15 is to be used continuously, there is, of course, no necessity for the track relay, and the control circuit and main circuit are always closed.

It will be noticed that the direct current which is used in the control circuit flows but 50% of 20 the time that the signal is in operation, thereby greatly decreasing the cost of operation.

Obviously the invention may be variously embodied within the scope of the appended claims and such modifications constitute a part of this 25 invention.

What I claim, therefore is:

1. A mercury switch comprising a glass envelope, a quantity of mercury therein, a displacer floating on the mercury, electrodes projecting into the envelope adapted to be bridged by the mercury when the displacer is in its depressed position, said displacer comprising a sleeve adapted to telescope over one of the electrodes and being relatively thick above the mercury level and relatively thin below said level. 35

2. A plunger for use in a mercury switch, said plunger comprising a sleeve having its upper portion of substantially greater thickness than its lower portion, said plunger being closed at 40 its upper end except for a restricted passage.

3. In an electromagnetic switch, a coil, a switch envelope, a quantity of mercury therein, electrodes projecting into the envelope and normally bridged by the mercury, a displacer floating on the mercury adapted to be raised to cause the mercury to recede in the envelope and break the connection between the electrodes, a time delay element associated with the displacer, said displacer comprising a sleeve having substantially greater mass at the top than at the bottom so that when the displacer is released from its raised position, it will fall at once to the floor of the envelope without coming to a position of floating equilibrium during its downward travel, and means for cushioning the fall of the displacer. 45

4. In an electromagnetic switch, a coil, a switch envelope, a quantity of mercury therein, electrodes projecting into the envelope and normally bridged by the mercury, a displacer floating on the mercury adapted to be raised to cause the mercury to recede in the envelope and break the connection between the electrodes, a time delay element associated with the displacer, said displacer comprising a sleeve having substantially greater mass at the top than at the bottom so that when the displacer is released from its raised position, it will fall at once to the floor of the envelope without coming to a position of floating equilibrium during its downward travel, and means for cushioning the fall of the displacer, said means including a spring interposed between the displacer and the floor of the envelope. 65

5. In an electromagnetic switch, a coil, a switch envelope, a quantity of mercury therein, electrodes projecting into the envelope and normally bridged by the mercury, a displacer floating on the mercury adapted to be raised to cause the mercury to recede in the envelope and break the connection between the electrodes, a time delay element associated with the displacer, said displacer comprising a sleeve adapted to telescope over one of the electrodes and having substantially greater mass at the top than at the bottom so that when the displacer is released from its raised position, it will fall at once to the floor of the envelope without coming to a position of floating equilibrium.
6. In an electromagnetic switch, a coil, a switch envelope, a quantity of mercury therein, a displacer for shifting the mercury level, a time delay element associated with the displacer, electrodes projecting into the mercury adapted to be bridged by the mercury when the coil is de-energized, said displacer having its upper portion of substantially greater dimensions than its lower portion so that when the coil is energized, the displacer will move promptly to its raised position after which the time delay element functions to provide a time interval before the circuit is opened, and when the coil is thereafter de-energized the displacer will fall promptly to the floor of the envelope after which the time delay element functions to delay the closing of the circuit.
7. In an electromagnetic switch, a coil, a switch envelope, a quantity of mercury therein, electrodes projecting into the envelope adapted to make or break an electrical circuit according to the mercury level, a displacer telescoped over one of the electrodes and responsive to the coil for shifting the mercury level, a time delay element associated with the displacer, said displacer having its mass so distributed with reference to the mercury level and the electrodes that movement of the displacer in both directions in response to the coil is characterized by relatively quick positive action to the full extent of the displacer travel after which the time delay element effects the delay in changing the condition of the circuit.
8. For use in a self-acting intermittent relay in which the relay coil is in series with the relay circuit breaker, the combination of a switch envelope, electrodes projecting into the envelope adapted to make or break an electrical circuit through the electrodes according to its level, a displacer responsive to the coil for changing the mercury level, a time delay element associated with the displacer, said displacer having its mass so distributed with reference to the mercury level and the electrodes that movement of the displacer in both directions in response to the coil is characterized by relatively quick positive action to the full extent of the displacer travel, after which the time delay element effects the delay in changing the condition of the circuit.
9. In a mercury switch, a switch envelope, a mercury fill, two or more electrodes adapted to be bridged under certain conditions by the mercury to close an electrical circuit through the switch, a displacer adapted to be raised by magnetic force and lowered by gravity to change the level of the mercury and hence the condition of the circuit through the electrodes, said displacer having substantially more mass above the high mercury level than below said level, so that when the displacer is released from its raised position it will immediately fall to its lower position with a sharp quick movement.
10. In a mercury switch, a switch envelope, a mercury fill, two or more electrodes adapted to be bridged under certain conditions by the mercury to close an electrical circuit through the switch, a displacer adapted to be raised by magnetic force and lowered by gravity to change the level of the mercury and hence the condition of the circuit through the electrodes, said displacer having substantially more mass above the high mercury level than below said level so that when the displacer is released from its raised position, it will immediately fall to its lower position with a sharp quick movement, and a time delay element associated with one of the electrodes.

CARL H. LARSON.
